UNITED STATES PATENT OFFICE.

CLARENCE S. DETRO, OF ASHLEY, PENNSYLVANIA.

STEAM-VALVE.

SPECIFICATION forming part of Letters Patent No. 259,827, dated June 20, 1882.

Application filed March 16, 1882. (No model.)

To all whom it may concern:

Be it known that I, CLARENCE S. DETRO, of 5
Ashley, in the county of Luzerne and State of
Pennsylvania, have invented certain new and
useful Improvements in Steam-Valves, of which
the following is a specification, reference being
had therein to the accompanying drawings.

My invention relates to rotary balanced
valves; and it consists in the construction and
arrangement of its several parts, as will be
hereinafter fully set forth, and pointed out in
the claims.

In the drawings, Figure 1 is a side elevation
of the exterior of the valve-chest; Fig. 2, a view
15 of the same, showing the position of the interior
parts in dotted lines; Fig. 3, a top plan
view of the plug; Fig. 4, a top plan view of the
casing, showing in dotted lines the arrangement
20 of the interior parts; Fig. 5, an end elevation;
Fig. 6, a vertical cross-section of the large
end of the valve and chest; Fig. 7, a vertical
cross-section taken a short distance to the
25 rear of Fig. 6; Fig. 8, a vertical cross-section
at the rear end of the valve. Fig. 9 is a vertical
longitudinal section of the plug. Fig. 10 is a vertical
longitudinal section of the valve-casing, and Fig. 11 an end view of the same.

A is the valve-casing, and is made of the
form shown and of sufficient size to afford
30 space within it for the plug and necessary
steam and exhaust ports, as will be hereinafter
fully set forth. Its lower portion is extended
outwardly in the form of a plate, a, and bolts
35 onto the cylinder-saddle, the upper edge of
which is shown at 1, Fig. 1. Increased thickness
of metal is shown in the surface of the casting
at a' and a² for the passage of the steam-
ways mentioned above. The rear end of the
40 cylindrical portion of the chest or cylinder is
closed by a head, a³, which may be bolted or
cast to it, as shown. The forward end of the
chest or cylinder is larger than the rear end,
in order to accommodate the tapering form of
45 the plug, and has bolted to it the head a⁴,
through which operates the large end of the
plug. Within the head is arranged a suitable
stuffing-box and a flange, a⁵, to prevent leakage.
The forward portion of the cylinder is
50 also provided with an annular recess, a⁶, which
affords sufficient space to prevent wire-draw-
ing of the steam. The interior of the cylinder
tapers from the forward end of its upper side

the entire length the plug penetrates it, when
it continues straight, as shown.

Extending along the bottom of the cylinder 55
is the exhaust-port 2, and arranged each side
of the exhaust-port, a suitable space intervening,
are the cylinder-ports 3. They extend
downwardly through the bottom portion, a, of
the chest, and connect with the steamways in 60
the cylinder-saddle. The entrance-ports a⁴ extend
from the outer lower edges of the cylinder
upwardly around its sides, and have inlet
into the steam-space a⁸ in the forward portion
of the cylinder through ports a⁵ in its upper 65
portion, as shown.

B is the plug. It consists of a round tapering
hollow portion, b, and a round hollow head, b',
which projects through the head of the cylinder
and has attached to it the rocker-arm b². 70
The lower side of the portion b is made solid,
and has arranged in its lower side the exhaust-
cavity b³. The cut-off ports b⁴ are arranged
upon each side, and above the exhaust-cavity
communicate with the interior of the plug, and 75
are arranged slightly in a diagonal position,
that they may communicate along their entire
length with the cylinder-ports, which are also
arranged in like manner, as shown. Steam is
admitted to the interior of the plug through a
recess, b⁵, cut between the body b and head b'
of the plug, and shown in Fig. 9. When the
plug is in position this recess is upward and
communicates freely with the space a⁶. The
head b' of the plug is also made hollow, so 80
that additional steam-room may be secured,
and also to prevent the entire pressure of the
steam from pressing the plug into the casing.
Upon the upper side of the plug, and running
its entire length, is a groove, c, and extending
85 from the large end of the plug, upon each
side of the groove c, and connecting with it at
different points along its course, are supple-
mentary grooves c'. Around the small end of
the plug, and communicating with the steam, 90
are arranged short notches c², as shown. There
are also notches c³ cut in the large end of the
cylinder, as shown. The object of these notches
and grooves is to counteract the force exerted
by the steam to press the plug into the valve 95
by exerting a pressure in the opposite direc-
tion, and thus making a perfectly-balanced
valve. The steam entering the large end of
the valve through the recess b⁵ travels along

the grooves c and c' into the steam-space behind the small end of the valve, and exerts a counteracting pressure against the plug. The notches c^2 and cylinder-notches c^3 also aid in preventing the valve from binding. The notches c c' also act as lubricators, an oil-cup being situated at any convenient place upon the medium line of the cylinder. In the operation of the valve a rocking motion is communicated to the plug by the rocker-shaft. The steam enters the interior of the plug, passes into the cylinder-ports through each cut-off port alternately, and escapes through the exhaust-cavity. The pressure on the valve is equalized by the admission of the steam to the rear end of the valve and by the notches, so that a free motion is secured. As the parts wear, the plug will of course sink farther into the cylinder. This is provided for by having the large end project slightly out of the bore. In the wearing of the plug a shoulder is prevented from forming in the small end of the cylinder, where the plug terminates, by the continuance of the bore parallel from that point, as shown.

What I claim is—

1. The plug B, having a central groove, c , and supplementary grooves c' , adapted to admit steam into the space behind the plug, and with notches c^2 , arranged around its small end, substantially as and for the purposes set forth.

2. The combination of the casing A, having entrance-ports a^4 , inlet-ports a^5 , steam-space a^6 , cylinder-ports 3, and exhaust-cavity 2, head a^7 , stuffing-flange a^8 , and notches c^3 with the plug B, having a hollow head, b' , which projects from the large end of the cylinder and has attached to it the rocker-arm b^2 , which connects with the actuating machinery, having steam recess or inlet b^5 , cut-off ports b^4 , and exhaust-cavity b^3 , and notches c , c' , and c^2 , all arranged to operate substantially as shown and described.

In testimony whereof I affix my signature in presence of two witnesses.

CLARENCE S. DETRO.
